(57) CLAIM

The ornamental design for bottle as shown and described.

DESCRIPTION

1. Bottle
- 1.1 : Perspective
- 1.2 : Front
- 1.3 : Right
- 1.4 : Top
- 1.5 : Bottom

The shadows and/or reflections that appear in the background of the reproductions are not part of the design for which protection is claimed. The broken lines depict portions of the bottle that form no part of the claimed design.
